Patented June 6, 1922.

UNITED STATES PATENT OFFICE.

CHARLES H. HYDE, OF WINSTED, CONNECTICUT, ASSIGNOR TO WILLIAM L. GILBERT CLOCK COMPANY, OF WINSTED, CONNECTICUT, A CORPORATION OF CONNECTICUT.

CLOCK CASE.

1,418,649.

Specification of Letters Patent. Patented June 6, 1922.

Application filed February 21, 1922. Serial No. 538,205.

To all whom it may concern:

Be it known that I, CHARLES H. HYDE, a citizen of the United States, residing at Winsted, county of Litchfield, State of Connecticut, have invented a certain new and useful Improvement in Clock Cases, of which the following is a full, clear, and exact description.

The present invention relates to clocks and 10 more particularly to metal alarm clocks, and has for its object to provide a novel and improved case for a clock of this character.

In the accompanying drawings:—

Figure 1 is a rear elevation, with a portion 15 of the gong broken away and with the winding and setting keys shown by broken lines, of a clock embodying the features of the invention in their preferred form;

Fig. 2 is a side elevation of the same; and 20 Fig. 3 is a sectional view taken on the line 3—3 of Fig. 1.

The metal alarm clock illustrated in the drawings is provided with a case 2 having a forward part 4 of sheet metal in the form of 25 a cylindrical shell and a back cover 6 of sheet metal on which the frame 7 of the clock mechanism is mounted. The back cover is provided with a cylindrical forwardly extending flange 8 that is telescopingly received in the rear portion of the forward part 4 of the case. The back cover and forward part of the case are detachably secured together by cap screws 10 which extend through rearwardly opening slots in 30 said forward part and are screw threaded into said flange. The cover abruptly tapers rearwardly from the flange 8 to form an annular shoulder 12 and then tapers more gradually to the rear wall 14 thereof. A 35 rearwardly extending portion 16 is pressed in the center of the back cover. The rear portion of the cover is enclosed by a gong 18 which is positioned against said projecting portion 16 and is secured thereto 40 by cap screws 20 extending through apertures in the gong and screw threaded into said projecting portion. The rear wall of the gong is substantially flat and its peripheral portion is curved forwardly to form a 45 flange 22 of substantially the same diameter as said forward part 4 of the case. The forward edge of the gong flange is spaced slightly away from the rear part 4 of the case and all of the gong is spaced away from 50 the cover 6 with the exception of its central

portion which is secured to the projecting portion 16 of the cover, so that the gong is free to vibrate. The clock is provided with the usual forward legs 24 which are secured to the forward part of the clock case. The 60 clock is provided with a rear leg 26 which as illustrated is in the form of a tongue having a horizontal portion 28 which is secured in a transverse depression 30 in the flange 8 of the back cover by a rivet 32 extending through the tongue and flange. The leg 26 is bent downwardly at right angles from 65 said horizontal portion so as to extend through the space between the edges of the gong and the forward part of the clock case, 70 this portion of the leg being positioned against the rear edge of the forward part of the clock case and spaced from the forward edge of the gong so as not to interfere with the vibration of the gong. The rear 75 leg is bent rearwardly beneath the gong to form a rearwardly and downwardly inclined supporting portion 34.

The frame of the clock mechanism is secured to the rear cover 6 so that this clock 80 mechanism is carried by the cover and removable therewith.

It will be apparent from the foregoing 85 that an easily removable cover is provided; that the cover carries the rear supporting leg, and that the gong is secured directly thereto without the usual spacing spider, thus doing away with extra parts and reducing the number of operations during the process of assembling. Moreover the edge 90 of the bell being in line with the front portion of the casing produces an attractive stream-line effect, substantially all parts of the rear cover being concealed so that the only metallic parts of the casing exposed to 95 view are the front part of the casing and the gong.

What I claim is:

1. A metal alarm clock of the class described having, in combination, a clock case 100 having a forward part of sheet metal in the form of a cylindrical shell, a back cover having a flange telescopingly received within the rear portion of said forward part of the case, a gong having a forwardly projecting 105 peripheral flange of the same diameter as said shell, said peripheral flange having its edge in line with and slightly spaced away from the rear edge of the forward part of the case, means for holding said 110

cover in place, front legs for the case, and a rear leg for the case, comprising a tongue-shaped member having its upper end portion secured to said flange and having its 5 remaining portion bent downwardly closely adjacent to the rear edge of said forward part to extend through the space between the edges of the gong and forward part of the case and then bent rearwardly to form a 10 rearwardly projecting supporting portion.

2. A metal alarm clock of the class described having, in combination, a clock case having a forward part of sheet metal in the form of a cylindrical shell, a back cover 15 having a forwardly extending flange telescopingly received within the rear portion of said forward part of the case, a gong having a forwardly projecting peripheral

flange of the same diameter as said shell, said peripheral flange having its edge in line 20 with and slightly spaced away from the rear edge of the forward part of the case, means for holding said cover in place, front legs for the case, and a rear leg for the case comprising a tongue shaped member having its upper end portion secured in an external depression in said flange and positioned between the flange and said forward part of the casing and having its remaining portion bent downwardly closely adjacent to the rear 30 edge of said forward part to extend through the space between the edges of the gong and forward part of the case and then bent rearwardly to form a rearwardly projecting supporting portion.

CHARLES H. HYDE.
